CONCENTRATED LIQUID DETERGENT

Edwin O. Korpi and Robert P. Davis, Cincinnati, Ohio, assignors to The Procter & Gamble Company, Cincinnati, Ohio, a corporation of Ohio

Filed Sept. 30, 1954, Ser. No. 459,240

5 Claims. (Cl. 252—153)

This invention relates to liquid synthetic detergent compositions, and particularly to those that are intended primarily for washing dishes, glassware, etc. in a dishpan or in a kitchen sink.

Such detergents, to be accepted by the user, should have certain characteristics—pourability, chill point well below normal room temperature, short reliquefaction time at room temperature after having been congealed by storage at low temperatures, good sudsing and detergent qualities; and above all, mildness to the hands of the user. While possessing all of these characteristics, the liquid detergent should be concentrated enough so that a moderate sized bottle or can of the liquid will provide detergent mileage for about as many dishwashings as a package of soap flakes or of synthetic detergent.

Many of the previously made liquid detergents were deficient in sudsing. The housewife is accustomed to having a sudsing detergent in the dishpan, and a low sudsing or non-sudsing detergent is handicapped.

For most housewives washing the dishes constitutes the longest exposure of the hands to a detergent solution.

It is an object of this invention to provide a liquid sulfated anionic detergent composition having characteristics desirable in such compositions and having, particularly, outstanding mildness to the hands of the user, and improved freeze recovery.

We have discovered that when the anionic sulfuric reaction product in a liquid detergent of the dishwashing type is composed of the sulfated and ammonia or substituted ammonia neutralized reaction product of about 3 moles of ethylene oxide and one mole of high molecular weight monohydric alcohol having from 10 to 16 carbon atoms in the molecule there is an unexpected improvement in freeze recovery and mildness to the hands. The high molecular weight alcohol used can be the "middle cut" produced in distilling the fatty alcohols derived from reducing coconut oil, coconut fatty acids, or their alkyl esters. Such middle cut fatty alcohols are the normal primary alcohols having 10 to 16 carbons in the molecule and obviously may be produced from other oils of the coconut group such as palm kernel and babassu.

After the approximately 3 moles of ethylene oxide have been reacted with the high molecular weight alcohol to produce the alkyl ethers the product is sulfated and the sulfuric half ester neutralized with ammonia or alkylol substituted ammonia. The alkylol substituted ammonias we prefer are mono-, di-, and triethanol, mono-, di-, and tripropanol, mono-, di-, and triisopropanol and mono-, di-, and triglycyl amines, those in which the alkylol group is of 2 to 3 carbon chain length.

The compound that makes the compositions of the present invention differ from those previously known is the sulfated and neutralized reaction product of about three moles of ethylene oxide with one mole of a high molecular weight alcohol. For this reason the first three examples that follow describe the preparation of reaction products of high molecular alcohols with ethylene oxide.

Example 1.—The condensation of ethylene oxide and

2

middle cut fatty alcohol from coconut oil was carried out in an autoclave, equipped with an agitator, an internal cooling coil, and an external electric heater. 23.45 parts of fatty alcohol were placed in the autoclave and sodium hydroxide pellets (0.25% based on the alcohol) were added. The cover was bolted onto the autoclave. The agitator was started and the external heater turned on. The autoclave was scavenged with nitrogen during the heating period which continued until a temperature of

10 270° F. was reached. At this point the heating coil was turned off, and 5.25 parts of ethylene oxide (1 mole per mole of alcohol) from a nitrogen blanketed weigh tank was allowed to flow into the autoclave. The reaction between the fatty alcohol and the ethylene oxide is exothermic, hence the cooling water was turned on through the internal cooling coil, and the flow of ethylene oxide was controlled so that the temperature did not rise above 305° F. and the pressure was held in the range of 60–80 p.s.i. After the ethylene oxide was all in the 15 autoclave, the reaction was allowed to proceed to completion as indicated by the pressure drop leveling off. After scavenging with nitrogen to remove the dissolved gases, and cooling, the autoclave was opened and the product removed.

20 25 Analysis indicates that this reaction product between 1 mole of ethylene oxide and 1 mole of middle cut fatty alcohol has the approximate following composition—molar percents.

	Molar percent
30 ROH	56
RO(C ₂ H ₄ O) ₁ H	22
RO(C ₂ H ₄ O) ₂ H	12
RO(C ₂ H ₄ O) _n H	10

35 where *n* is more than 2, and R is a mixture of alkyls from middle cut alcohol.

The reaction product of the above example was sulfated with 105% of the theoretical amount of chlorosulfonic acid at a temperature of 95° to 100° F.

40 Analysis indicated a 98% completeness of sulfation. The product was neutralized with ammonia. For convenience, the sulfated mixture of reaction products produced by reacting 1 mole of fatty alcohol with 1 mole of ethylene oxide is called alkyl (EtO)₁ sulfate, although it should be noted that the unreacted alcohol (56%) appears in this product as alkyl sulfate.

The product was suitable for use in the preparation of liquid detergent compositions in accordance with our invention.

50 *Example 2.*—Using the equipment and operating conditions described in Example 1, 18.35 parts of middle cut fatty alcohol, to which caustic soda pellets were added to the amount of 0.25% on the weight of the alcohol, were reacted with 12.35 parts of ethylene oxide. This is 55 3 moles of ethylene oxide to 1 mole of fatty alcohol. In this reaction the temperature went to 315° F. After scavenging with nitrogen and cooling, a portion of this product was analyzed. Its composition was approximately

	Molar percent
60 ROH	26
RO(C ₂ H ₄ O) ₁ H	15
RO(C ₂ H ₄ O) ₂ H	16
RO(C ₂ H ₄ O) ₃ H	15
RO(C ₂ H ₄ O) _n H	28

65 where *n* is more than 3 and R is a mixture of alkyls from middle cut CNO alcohol.

The reaction product was sulfated with 105% of the theoretical amount of chlorosulfonic acid. Analysis indicated a completeness of approximately 98%. The product was neutralized with ammonia. For convenience the product is called alkyl (EtO)₃ sulfate although ap-

proximately half of it is alkyl sulfate plus alkyl ethylene oxide condensation products with more than 3 ethylene oxides per mole of alcohol.

The product may be used in the preparation of a liquid detergent composition having the desirable characteristics set forth above.

Example 3.—Using the equipment and operation, conditions described in Example 1, 14.90 parts of middle cut alcohol to which 0.25% (on the alcohol) of caustic soda pellets were added, were reacted with 16.80 parts of ethylene oxide. This is five moles of ethylene oxide to one of alcohol. The temperature of this reaction rose to 305° F. After scavenging with nitrogen and cooling, the product was removed from the autoclave.

A portion was analyzed and found to have the following approximate composition in molar percents.

	Molar percent
ROH	9
$R(C_2H_4O)_1H$	9
$R(C_2H_4O)_2H$	12
$R(C_2H_4O)_3H$	13
$R(C_2H_4O)_4H$	11
$R(C_2H_4O)_5H$	10
$R(C_2H_4O)_nH$	36

where n is more than 5 and R is a mixture of alkyls from middle cut fatty alcohols.

This is evidence that n may be as high as 12 in this preparation since the data and calculations as presented in Figure 1 show that n is 11 or less in only 90% of the composition.

The reaction product was sulfated with 105% of the theoretical chlorosulfonic acid, and was determined to be about 98% sulfated.

The product was neutralized with ammonia. For convenience, this reaction product is called alkyl (EtO)₅ sulfate although the actual molar percent of the condensation product of fatty alcohol with 5 moles of ethylene oxide is only about 10%.

The product may be used in liquid detergent preparations meeting the objects set forth above.

In contrast with the foregoing uses of an alkaline catalyst, we have also carried out the condensations of high molecular alcohol with alkylene oxide using stannic chloride as the catalyst and boron trifluoride as the catalyst. The boron trifluoride was used as the ether complex, for convenience. These two acid catalysts have some advantages, particularly in their being workable at lower temperatures and correspondingly lower pressures. However, the corrosive character of these acid catalysts and the extra steps, such as water washing, required to remove the catalysts from the reaction product, have led us to prefer sodium or potassium hydroxide as the catalyst, which only needs neutralization with acid for its inactivation. However, we do not wish to limit ourselves to the use of sodium or potassium hydroxide as the catalyst.

The alkyl ethylene oxide ammonium sulfate products made according to the methods set forth in Examples 1, 2, and 3 were tested for dishpan sudsing against a commercial liquid dishwashing detergent in which the anionic sulfuric reaction product was ammonium alkyl sulfate, the alkyl being middle cut coconut alcohol.

The series of tests was carried out with amide builder.

In all four of the preparations the composition was:

37.5 parts by wt. of the neutralized anionic sulfuric reaction product.

12 parts of coconut monoethanol amide.

50.5 parts of water to make 100 parts total.

No ethyl or propyl alcohol was added as prior work showed these alcohols do not affect sudsing.

The coconut amide was made by reacting monoethanol amine with coconut fatty acids. The active builder portion of these amides is comprised essentially of the

amides of the C_{10} , C_{12} and C_{14} fatty acids. Other alkylol amines may be used in place of monoethanol amine, for example, diethanol amine, and mono- and dipropanol and isopropanol amines and mono- and diglyceryl amine may be considered substantial equivalents for the present purpose, thus producing alkylolamides with not more than three carbon atoms in each alkylol radical.

The dishpan sudsing test used in this composition determines the amount of detergent required to wash a standard number of soiled plates and have a definite suds level after the plates are washed. The plates are soiled with a mixture of tallow, salad oil, flour and powdered gelatin. Successive trials with varying amounts of detergent are made until the amount required to wash the plates and have a definite level of suds at the finish is determined. The tests on the preparations of Examples 1, 2, and 3 were made in water of 7 grains per gallon hardness.

According to this test, the performance of the compositions made by reacting 1 mole of ethylene oxide, and 3 moles of ethylene oxide, with one mole of fatty alcohol, were equal or better than a commercial product, Joy, a liquid detergent, containing ammonium neutralized fatty alcohol sulfate, built with coconut amide. The composition containing the reaction product of 5 moles of ethylene oxide with one mole of fatty alcohol was only slightly less efficient than the other compounds shown, and was also a satisfactory preparation.

If the choice of the number of moles of EtO to react with one mole of alcohol were based solely on the sudsing test, above, one or two moles of EtO per mole of high molecular alcohol would probably be chosen. However, the mildness to the hands of the user is the principal object of this composition. Mildness increases with the number of moles of EtO reacted with one mole of the high molecular alcohol. If mildness were our sole objective we would probably settle on 5 moles of EtO . This composition, however, when sulfated and neutralized does not suds quite as well as the one with 3 moles of EtO per mole of high molecular alcohol. Our choice therefore taking both mildness and detergency into consideration is the one made by reacting 3 moles of EtO with one of high molecular alcohol. However, the desirable qualities do not peak sharply at 3 EtO but spread out to include 2 and 4 EtO , and if a slight decrease in mildness is tolerated, would include 1 EtO and if a slight decrease in sudsing is tolerated, include 5 EtO .

The reason for these several preparations being approximately alike in their qualities may be inferred from Figure 1. In this is shown the molecular percentages of the various alkyl ethers when 1, 3, and 5 moles respectively of ethylene oxide are reacted with the fatty alcohol. In this presentation, the unreacted fatty alcohol has been taken out and only the mol percent of the several ethers shown on an alcohol free basis. Even the alkyl (EtO)₁ contains more than 5 mol percent of alkyl ethers containing five or more ethylene oxide groups. Each of the three condensation products represented by the three curves is a mixture of low and high polymers, the maximum amount of high polymers increasing of course, as more ethylene oxide is condensed with the fatty alcohol. The characteristics, obviously, blend from one preparation to another.

It may be stated that the values in Figure 1 were not obtained by direct analysis of the preparations shown in Examples 1, 2, and 3. When the alcohol used is the approximately C_{12} alcohol used in the examples and preparations, fractional distillation is only possible to about alkyl (EtO)₃. The data, in Figure 1 were obtained largely with preparations made by condensing ethylene oxide with C_8 alcohol. These were found to have the same molar percentage distribution as the C_{12} alcohols in the ranges where they could be checked and it is assumed that this holds in the upper ranges. Even using the C_8 alcohols some of the upper values are extrapolations but

we believe the values plotted in Figure 1 show the approximate relations between the three preparations even though the exact values may not be as portrayed.

The mildness advantage of the compositions of our invention has been thoroughly proven, and the following test results are typical.

We prepared (from middle cut coconut oil alcohols) a large batch of alkyl (EtO)₃ sulfate liquid detergent for clinical testing, the formula being

	Parts by weight
Ammonium alkyl (EtO) ₃ sulfate	37.5
Coconut monoethanol amide	9.0
Ethyl alcohol	22.0
Citric acid	1.0
Water	30.5
	100.0

This was tested against an alkyl sulfate liquid detergent, the alkyl radical being derived from a similar middle cut alcohol as used in the alkyl (EtO)₃ sulfate.

The formula was:

	Parts by weight
Ammonium alkyl sulfate	37.5
Coconut monoethanol amide	12.0
Ethyl alcohol	18.0
Citric acid	1.0
Water	31.5
	100.0

312 women who washed their own dishes were supplied the alkyl (EtO)₃ sulfate liquid detergent and 317 women who likewise did their own dishes were supplied the alkyl sulfate liquid detergent. The women used the liquid detergents for a period of two weeks, and then were examined by physicians. Neither the women nor the physicians knew which liquid detergent was used.

The physicians scored the condition of the skin of the hands of the users on a 1 to 10 scale. On this scale 10 is perfect and is only attained by a few persons who seem immune to the effects of detergents and water. On this scale, 1 is rather severe irritation, deep cracks appearing in the skin.

7.5 is the highest value ever obtained as the average of a clinical survey. At a value of 7.5 a superficial glance would lead to the conclusion that the skin was unaffected, but closer and particularly microscopic examination would reveal minor cracks and scaling.

After the physicians rated the hands of the users, the results were compiled by a person who had a list of the users and the liquid detergent used. The average of each group was multiplied by 10 to give a 10 to 100 scale. The scores were:

Alkyl (EtO) ₃ sulfate liquid detergent	69.9
Alkyl sulfate liquid detergent	65.3

On a scale where 75 represents the average of a clinical test of the mildest detergent ever tested, this difference is significant. Statistical analysis shows that a difference of only 2.7 gives a 95% assurance of a difference when rated on a scale of values according to which 100 represents unattainable perfection as an average and 75 represents the average of the mildest detergent ever tested.

One of the unexpected advantages of the alkyl (EtO)₃ sulfate liquid detergent is rapid freeze recovery. This test is made by holding the product in a test tube, about 15 mm. inside diameter, at a low temperature for 4 days at which the composition clouds and/or freezes. It is then brought into a room at about 75° F. and the time to reach clarity is noted. Clarity is defined as the condition where no observable solid or congealed matter exists.

For comparison the freeze recovery time of a commercial liquid detergent in which the anionic active is ammonium alkyl sulfate is 24 hours.

A series of alkyl (EtO)₃ sulfate liquid detergents was made up as follows.

Example 4.—The reaction product of three moles of ethylene oxide and one mole of middle cut coconut alcohol was sulfated and neutralized with ammonia.

A liquid detergent was made from this alkyl (EtO)₃ sulfate using the following formula.

	Parts by weight
Alkyl (EtO) ₃ sulfate	36
Coconut monoethanol amide	8.6
Ethyl alcohol	19.5
Water to make 100 parts	35.9

Portions of this were placed in test tubes and held for five days at 50° F. No clouding occurred. Four test tubes were filled with portions and held for 4 days at 0° F., 20° F., 30° F., and 40° F. respectively. They were then brought into a space maintained at 75° F. and they all regained their clarity in less than 4 hours.

Monoethanolamine, diethanolamine and triethanolamine or the corresponding isopropanolamines may be used in place of ammonia, to neutralize the sulfate with no significant change in the characteristics of these compositions.

Example 5.—Another preparation was made from the materials of Example 4, but the proportions were as follows:

	Parts by weight
Alkyl (EtO) ₃ sulfate	37.5
Coconut monethanol amide	9.0
Ethyl alcohol	20.5
Water to make 100 parts	33.0

Portions of this preparation were placed in test tubes, and four of them were placed in spaces held at 0° F., 20° F., 30° F., and 40° F. respectively. After four days, the tubes were moved to a space held at 75° F. All cleared in less than 4 hours. One tube was held at 50° F. for 5 days and it remained clear.

Another consideration affecting the amounts of ethyl or propyl or isopropyl alcohol used as a solvent, is the effect of these alcohols on the viscosity of the liquid detergent. Increasing the alcohol content—the water being correspondingly decreased—lowers the viscosity.

With the preparations of our invention, the ethyl or propyl alcohol used as a solvent will be about 15% to 25% by weight of the liquid detergent as it is ready for use and enough to maintain the amide and detergent in solution but not enough to cause precipitation or cloudiness.

The coconut monethanol amide in Example 4 was 8.6%, whereas in the dishpan sudsing tests used in testing the products of Examples 1, 2 and 3, the amide was 12%. The objects of our invention can be achieved by amounts of the above amide or propanol coconut amide between about 6 and 12% of amide.

While we speak of the alkyl (EtO)_n sulfates, and the coconut amides as if they were pure compounds, this is not exactly true. There are unreacted alcohols, salts of sulfuric and hydrochloric acid (from chlorosulfation) amine soaps and other extraneous substances, which may total 5% on the whole composition.

It is important to control the ammonium and substituted ammonium salts of sulfuric and hydrochloric acid, called for convenience electrolyte salts. After chlorosulfation, the hydrochloric acid not driven off during the process is there as free acid. This is driven off by aeration to, preferably, the amount that will produce not over 0.5% NH₄Cl (finished product basis) when neutralized with ammonia. Up to 1% NH₄Cl may be tolerated but a limit of 0.5 NH₄Cl is preferable. If substituted ammonias are used, the amine chlorides should be held down to the stoichiometric equivalents of the above values for NH₄Cl. The SO₃ portion of the chlorosulfonic acid is not all used up in sulfation, about 5% of the acid used ending up as H₂SO₄ in the reacted mix. This will produce about 0.6

$(\text{NH}_4)_2\text{SO}_4$ in the finished product. It will be appreciated that the determination of the amount of ammonium or amine sulfates in the presence of such large amounts of ammonium or amine alkyl (EtO_n) sulfates is not precise. The values for sulfate electrolyte salts given, are our best estimates. Experiments with added sulfate have indicated that about 1% ammonium sulfate basis is all that can be tolerated. If these electrolyte salts are not held at the low levels indicated, the product will have a poor chill test and freeze recovery, and with high sulfates may separate into two layers. The tolerance of the preparations of our invention for electrolyte salts depends upon the amount of alcohol present. For this reason the electrolyte salts are held to a practical minimum. Obviously the electrolyte salts are present in direct proportion to the alkyl (EtO_n) sulfate. Our electrolyte salts are therefore present preferably in the amount of $(.6+.5)/37.5\%$ or just under 3% of the alkyl (EtO_n) sulfate and the maximum tolerated would be about $(1+1)/37.5$ or 5.4% of the alkyl (EtO_n) sulfate.

Since a liquid detergent is poured in small amounts into a dishpan or sink containing a large amount of water it will be perceived that the concentration of the detergent materials in the bottle or can may be varied. The lower limit of concentration is set by the requirements that the container ought to contain about as many "washes" as a box of soap or synthetic detergent without being so large as to be expensive or clumsy. About 25% of the sulfated and neutralized condensation product of higher fatty alcohol and ethylene oxide is a satisfactory lower limit. The upper limit is set by considerations of the pourability of the alcohol-water solution of the active ingredients. With alkyl (EtO_n) sulfates this limit is at about 40%. With the overlapping of species of polymers as shown on Figure 1, it is also evident that the number of moles of ethylene oxide reacted with 1 mole of fatty alcohol may be varied over a rather wide range. While 3 moles of ethylene oxide seems a good optimum value for mildness and sudsing, it is evident that 2 moles or 4 moles will give results differing very little from 3 moles, and even 1 to 5 moles have significant advantages of mildness and freeze recovery over other anionic detergents in liquid detergent compositions. Since the distribution of species is so wide, in the ethylene oxide fatty alcohol condensation, there is no point in having an integral number of moles of ethylene oxide per mole of fatty alcohol. For example, if 3 moles is optimum, one can approximate these results with any amount between 2 and 4 moles.

To show the allowable variation in composition the following examples were made from middle cut coconut alcohol with ammonia neutralization of the sulfate.

	Example 6	Example 7	Example 8
Alkyl (EtO_3) sulfate.....	36	39	40 $\frac{1}{2}$
Ethyl alcohol.....	19 $\frac{1}{2}$	21 $\frac{1}{2}$	23
Coconut ethanol amide.....	8.7	9.35	9.75
Clouding 5 days at 40-50° F.....	none	none	none
Freeze recovery after 4 days at 0° F.....	O.K.	O.K.	O.K.

These preparations were equal or better than a commercial liquid dishwashing detergent in sudsing and pourability.

It will be evident to those skilled in the art that there is a set of complex relationships among the ingredients of the liquid detergent of our invention. At a given level of alkyl (EtO_3) sulfate the more amide that is used, the more the percent alcohol will have to be increased.

The more alcohol that is used, the greater is the tendency of the electrolyte salts to interfere with clarity and freeze recovery. The alcohol has to be adjusted to the point where it holds the amide in solution, but does not cause the electrolyte salts to interfere with clarity.

It is evident that our disclosures will allow relatively wide variations in proportion, without departing from the spirit of the invention.

Having thus described our invention, we claim:

5 1. A single phase concentrated liquid detergent composition consisting essentially of a solution of

(a) 25 to 40% of a sulfated and neutralized reaction product obtained from condensing 1 to 5 moles of ethylene oxide and 1 mole of monohydric alcohol of from 10 to 16 carbon atoms in the molecule, said reaction product including unreacted alcohol and otherwise consisting essentially of a mixture of fatty alcohol-ethylene oxide ethers of the general formula of

where R represents an alkyl chain of 10 to 16 carbon atoms in the alkyl radical, x is a plurality of whole numbers within the range from 1 to 12 inclusive, said unreacted alcohol and mixed alkyl ethers being sulfated, and then neutralized with a neutralizing agent selected from the group consisting of ammonia and alkylol-substituted ammonia having from 2 to 3 carbon atoms in the alkylol group;

(b) An organic builder substance consisting essentially of alkylol-amide of saturated fatty acids having 10, 12 and 14 carbon atoms and an alkylol amine, said alkylol amide having not more than 3 carbon atoms in each alkylol radical and the amount thereof being from 6 to 12% of the composition;

(c) 15 to 25% of alcohol from the group consisting of ethanol, normal propanol and isopropanol;

(d) Not over 5% of extraneous substances (such as sulfates and chlorides of the ammonia or substituted ammonia used, plus unsulfated alkyl ethers and other reaction products);

(e) Water to make 100%, said composition being stable against clouding, precipitation of solids, and gelling at temperatures as low as 50° F., and with a freeze recovery of 4 hours or less.

40 2. A single phase concentrated liquid detergent composition consisting essentially of a solution of

(a) 25 to 40% of a sulfated and neutralized reaction product obtained from condensing 2 to 4 moles of ethylene oxide and one mole of monohydric alcohol of from 10 to 16 carbon atoms in the molecule, said reaction product including unreacted alcohol and otherwise consisting essentially of a mixture of fatty alcohol-ethylene oxide ethers of the general formula of

55 where R represents an alkyl chain of 10 to 16 carbon atoms in the alkyl radical, x is a plurality of whole numbers within the range from 1 to 12 inclusive, said unreacted alcohol and mixed alkyl ethers being sulfated, and then neutralized with a neutralizing agent selected from the group consisting of ammonia and an alcohol substituted ammonia having from 2 to 3 carbon atoms in the alkylol group;

(b) An organic builder substance consisting essentially of alkylol amide of saturated fatty acids having 10, 12 and 14 carbon atoms and an alkylol amine, said alkylol amide having not more than 3 carbon atoms in each alkylol radical and the amount thereof being from 6 to 12% of the composition;

(c) 15 to 25% of alcohol from the group consisting of ethanol, normal propanol and iso propanol;

(d) Not over 5% of extraneous substances (such as sulfates and chlorides of the ammonia or substituted ammonia used, plus unsulfated alkyl ethers and other reaction products);

(e) Water to make 100%, said composition being stable against clouding, precipitation of solids, and gelling, at temperatures as low as 50° F., and with a freeze recovery of 4 hours or less.

3. A single phase concentrated liquid detergent composition consisting essentially of a solution of

(a) 25 to 40% of a sulfated and neutralized reaction product obtained from condensing 1 to 5 moles of ethylene oxide and 1 mole of fatty alcohol, said fatty alcohol being a straight chain primary alcohol of 10 to 16 carbons and having a terminal hydroxyl group, said reaction product including unreacted alcohol and otherwise consisting essentially of a mixture of fatty alcohol-ethylene oxide ethers of the general formula of

where R represents an alkyl chain of 10 to 16 carbon atoms in the alkyl radical, x is a plurality of whole numbers within the range from 1 to 12 inclusive, said unreacted alcohol and mixed alkyl ethers being sulfated, and then neutralized with a neutralizing agent selected from the group consisting of ammonia and an alkylol substituted ammonia having from 2 to 3 carbon atoms in the alkylol group;

(b) An organic builder substance consisting essentially of alkylol amide of unsaturated fatty acids having 10, 12 and 14 carbon atoms and an alkylol amine, said alkylol amide having not more than 3 carbon atoms in each alkylol radical and the amount thereof being from 6 to 12% of the composition;

(c) 15 to 25% of alcohol from the group consisting of ethanol, normal propanol and iso propanol;

(d) Not over 5% of extraneous substances (such as sulfates and chlorides of the ammonia or substituted ammonia used, plus unsulfated alkyl ethers and other reaction products);

(e) Water to make 100%, said composition being stable against clouding, precipitation of solids, and gelling, at temperatures as low as 50° F., and with a freeze recovery of 4 hours or less.

4. A single phase concentrated liquid detergent composition consisting essentially of a solution of

(a) 25 to 40% of a sulfated and neutralized reaction product obtained from condensing 2 to 4 moles of ethylene oxide and 1 mole of fatty alcohol, said fatty alcohol being a straight chain primary alcohol of 10 to 16 carbons and having a terminal hydroxyl group, said reaction product including unreacted alcohol and otherwise consisting essentially of a mixture of fatty alcohol-ethylene oxide ethers of the general formula of

where R represents an alkyl chain of 10 to 16 carbon atoms in the alkyl radical, x is a plurality of whole numbers within the range from 1 to 12 inclusive, said unreacted alcohol and mixed alkyl ethers being sulfated, and then neutralized with a neutralizing agent selected from the group consisting of ammonia and an alkylol substituted ammonia having from 2 to 3 carbon atoms in the alkyl group;

(b) An organic builder substance consisting essentially of alkylol amide of saturated fatty acids having 10, 12 and 14 carbon atoms and an alkylol amine, said alkylol amide having not more than 3 carbon atoms in each alkylol radical and the amount thereof being from 6 to 12% of the composition.

(c) 15 to 25% of alcohol from the group consisting of ethanol, normal propanol and iso propanol;

(d) Not over 5% of extraneous substances (such as sulfates and chlorides of the ammonia or substituted ammonia used, plus unsulfated alkyl ethers and other reaction products);

(e) Water to make 100%, said composition being stable against clouding, precipitation of solids, and gelling, at temperatures at low as 50° F., and with a freeze recovery of 4 hours or less.

5. The liquid detergent composition of claim 4 in which the straight chain primary alcohol constituent is a middle cut coconut alcohol mixture and in which the number of moles of ethylene oxide per mole of fatty alcohol is approximately 3.
